GRACE HUDSON.

FURNACE.

1,152,332.

Specification of Letters Patent. Patented Aug. 31, 1915.

Application filed July 21, 1910. Serial No. 573,109.

To all whom it may concern:

Be it known that I, MARY A. MALLOY, a citizen of the United States, and a resident of Portland, in the county of Multnomah, State of Oregon, have invented a new and useful Improvement in Furnaces, of which the following is a specification.

This invention relates to furnaces, referring by this word to any device in which is built a fire to generate heat for any purpose.

The object of my invention is to so improve the construction and arrangement of a furnace as to enable the perfect control of the fire; also to cause a more perfect combustion than obtained in furnaces as heretofore constructed; incidentally to obtain greater heating value from the fuel, and to conserve the fuel on the grate, using it only proportionately to the degree of heat desired, and to obtain this result regardless of the quantity of fuel on the grate; also to so arrange the furnace as to prevent any great loss of heat up the chimney, and consequent waste of fuel; also to provide means by which the fire, with but little attention, may be retained indefinitely at a constant degree of heat until all the fuel on the grate is consumed, and to obtain this result regardless of the quantity of fuel on the grate; also to avoid all danger of explosion because of undue accumulation of gases in the combustion chamber of the furnace. In order to attain these results, the furnace, whatever its size or shape, must embody certain features: It must be provided with a grate to support the fuel, and must have a combustion chamber which is sealed above the grate against the ingress of air above the grate. It must have a draft chamber below the grate, and such draft-chamber have an air-inlet controlled by an adjustable gate, and the latter adapted to continuously admit a minimum volume of air, even when entirely closed. The furnace must, further, not be directly connected to the flue of the stack, but instead the draft and the waste products of combustion must be drawn through a passage-way always open and connecting the upper part of the combustion chamber with a controlling-draft chamber separated from the draft-chamber and having an outlet, constantly open, to the flue of the stack; and said controlling-draft

chamber must be provided with an air inlet controlled by an adjustable gate. Furthermore, the gate-controlled air-inlet of the draft chamber, the gate-controlled air-inlet of the controlling-draft chamber, and the cross-section of the outlet to the chimney from said controlling-draft chamber must be relatively proportioned, as hereinafter fully set forth.

In the drawings constituting a part of this specification: Figure 1 is a central vertical section illustrating my invention as embodied in a type of parlor stove burning common fuel; Fig. 2 is a front elevation of the same stove; Fig. 3 is a horizontal section of the door of the fuel inlet provided in the upper part of the casing of the combustion chamber of my stove; Fig. 4 is a horizontal section of the door of the draft chamber located directly below the grated bottom of the combustion chamber; Fig. 5 is a horizontal section taken on a line A—A of Fig. 1; Fig. 6 is a central vertical section of a parlor stove similar in type to that shown in Fig. 1, excepting that the passageway from the combustion chamber to the controlling-draft chamber, instead of being a single duct as shown in Fig. 1, is divided into two sections, located at the sides, so as to provide a greater fuel space on the grate, as more clearly shown in the horizontal section, Fig. 7, which is approximately taken on a line B—B of Fig. 6. Fig. 6 also illustrates the top of the casing of the combustion chamber as provided with an angular pocket, and the top consisting of a plate having pendent flanges seated in said pocket, and an upwardly projecting rim rendering the top plate serviceable for a vessel in which to heat water; Fig. 8 is a sectional detail illustrating a convenient manner of arranging a trap door in the bottom of the draft chamber, in order to permit the dumping of accumulated ashes onto the floor of the controlling-draft chamber, located below the draft chamber; and Fig. 9 shows a portion of the front wall of the controlling-draft chamber and illustrates a means for so hinging the door *h* of the controlling-draft chamber *g* as to stand merely ajar, and not wide open when unlatched.

Referring in the first instance to the construction illustrated in Fig. 1, it will be

noted that the casing is vertically divided into a combustion chamber, *a*, which is provided with a grate *b* in the bottom. Below the grate, *b*, is a draft chamber, *c*, which constitutes also an ash-pit. This chamber is provided with an opening or air-inlet *d*, covered by a gate *e*, of the construction illustrated in Fig. 4; said gate having a series of perforations *f*, so that when the gate *e* is entirely closed there will still be admitted a continuous minimum flow of air into the draft-chamber, and thence through the grate bars *b*. However, instead of a series of perforations as *f* in the door, any means adapted to permit the constant inflow of a minimum volume of air, when the gate is closed, will answer. Below the draft-chamber *c* is provided a controlling-draft chamber *g*, having a door *h* provided with an air-inlet *i* controlled by a gate *j* adjustable by a latch 18. The air-inlet *i* must be close to the bottom of the chamber *g*. The upper part of the combustion chamber, *a*, is connected by a passage-way *k* with the upper part of the controlling-draft chamber *g*. This passage-way may be a pipe arranged as shown in Fig. 1. The chamber *g* is provided with an outlet, *m*, to the flue of the stack, the connection with such flue being made in any convenient manner. There must be no damper in either the smoke duct *k* or in the outlet *m* to the chimney. The controlling-draft chamber must be deep enough to allow the smoke duct to extend above the bed of fuel, so as to keep the heated gases drawn from the combustion chamber, through the passage-way *k*, into controlling-draft chamber *g*, and the cold air, drawn into the latter through its air-inlet *i*, separated from each other; that is to say, if the chamber *g* is properly proportioned, as mentioned, the cold, heavier air flowing in through inlet *i* will keep to the bottom of such chamber, following approximately the lower course indicated by the arrows *c a*, through outlet *m*, while the hotter gases, drawn from the combustion chamber, will follow approximately the upper course, indicated by the arrows *h a*, through outlet *m*. That this is true may be readily ascertained by applying the hand to the outlet *m*. It will be found warm at the top and comparatively cold at the bottom. This result is one of the most important features of my furnace. For this reason the air-inlet *i* is located close to the bottom of the chamber *g*. For if the cold lower draft, admitted into the chamber *g*, comes into contact with the draft drawn in at the top of the chamber *g* from the combustion chamber, such lower draft, being so much stronger than the upper, is liable to cut off the latter, choke it as it were, which would not only interfere with the proper working of my furnace, but cause an excessive and explo-

sive accumulation of gases in the combustion chamber. On the other hand, in my construction, any such dangerous condition is absolutely prevented, and could not possibly be brought about.

The minimum air-inlet of the draft-chamber *c*, the maximum air-inlet of the controlling-draft chamber *g*, and the cross-section of the outlet *m* of the latter, must be relatively proportioned. The maximum volume of air admitted through the gate-controlled inlet *i* of the controlling-draft chamber *g* must not exceed approximately two-thirds of the cross-section area of the outlet *m*, and the minimum volume of air constantly admitted through the gate-controlled inlet *d* of the draft-chamber must not be less than approximately one-sixth of the cross-section of the outlet *m*. Thus when the gate *j* of the air-inlet of the controlling-draft chamber is wide open I still have one-third in area of the draft up the chimney drawing through the combustion chamber. By proportioning the parts as mentioned, the gates of the air-inlets of the draft-chamber and the controlling-draft chamber provide reliable means for controlling the intensity of the fire in my stove according to existing conditions and requirements. These features also render my furnace an efficient heating device for all altitudes and climates.

The principle of operation of my furnace will now be readily understood. The draft of the chimney is apportioned between, and changeable from, the draft-chamber *c* to the chamber *g*, and vice versa. The admission of air through the draft-chamber *c* is adjustable for limiting the air-draft to the fuel proportionately to the desired degree of heat. The two streams of air simultaneously drawn by the chimney through the chambers *c* and *g*, respectively, may be said to be balanced, either one being relatively increased as the other is proportionately decreased. This result is attained because the gate-controlled air-inlets of said chambers *c*, *g*, and the outlet from the chamber *g* to the chimney are, respectively, relatively proportioned as described.

By opening slightly the door *h* of the controlling-draft chamber *g*, and closing the gate of the air-inlet of the draft-chamber *c*, the strong air suction of the chimney through the chamber *g* cuts off the weaker draft through the chamber *c*, and the fire will consequently die out in a short time. In order to accomplish this result, however, the combustion chamber, *a*, above the grate, *b*, must be sealed against the ingress of air, as mentioned; for, if there should be any leakage of air into the combustion chamber, the drafts could not be efficiently controlled and the fire might continue burning, notwithstanding, until all the fuel on the grate is consumed.

The described construction also enables me to so adjust the drafts as to keep a steady, economical and efficient fire indefinitely; in other words, using up the fuel in a most economical manner, regardless of the quantity of fuel on the grate, at the same time getting a constant and continuing degree of heat, until all the fuel on the grate is consumed. And all the attention my furnace 10 requires for this purpose is an occasional shaking of the grate.

For a slow steady fire the gate *j* of the air-inlet *i* of the door of the controlling-draft-chamber *g* is opened wide, and the gate *e* of the air-inlet *d* of the draft-chamber *c* may be closed entirely, since its perforations will still admit sufficient air to keep the fire alive, and prevent undue accumulation of gases and danger of explosion. This result could 20 not be had in furnaces of common construction for obvious reasons.

By reason of my furnace being air-tight at the top and sides, above the grate, all the air which enters into the combustion chamber must, in the first instance, pass through the grate and the bed of coals thereon, thus becoming heated. The waste gases, being very much lighter than air, are easily drawn off by a gentle draft through the passage-way *k* into the controlling-draft chamber, and thence up the flue of the stack, while the heat is held in and radiated from the dome or upper part of the combustion chamber.

In order to replenish the fuel while there is still a fire in my furnace, the draft through the gate of the air-inlet of the chamber *c* must be closed, and the gate of the controlling-draft chamber *g* opened, and after a few minutes the bed of fuel on the grate *b* will have only a slight fire on the under side, but no smoke. The fuel bed must not be stirred, but the fresh fuel placed on top thereof, and then the fuel-opening of the casing, *a*, is closed up air-tight again. The gate *j* of the controlling-draft chamber *g* is then closed and the gate *e* of the draft-chamber *c* is opened wide until the fire is burning brightly, then the gate *j* of the controlling-draft chamber *g* should be opened sufficiently to prevent the flame and heat from being drawn up the chimney. After a while both drafts are adjusted, as required, to obtain a constant temperature of the desired degree.

The frame of the door, *o*, of the fuel inlet, *n*, must have an air-and-gas-tight contact with the casing portion to which it is attached. The gate *e* of the draft chamber *c* must have a substantially air-tight fit at its rim with the casing against which it abuts, for otherwise the amount of air admitted through the aperture of the door could not be as efficiently regulated.

The bottom of the combustion chamber 65 may be arranged as more clearly illustrated

in Fig. 5. The grated member *l* has an aperture *q*, in which is rotatably seated a circular grated plate *r*. The member *l* rests on lugs *s* and is adapted for lateral movement by the handle *t*, for shaking down the ashes; and the member *r* may be rotated on its pivots by the handle *u*.

If deemed convenient, the bottom *v* of the chamber *c* may be provided with an opening (see Fig. 8) closed by a hinged trap-door *w*. 75 The rim of the opening for the latter is made with a flange *x* to provide a seat for a removable plate *y*, preferably provided with an asbestos under face. See Figs. 1 and 6. The purpose of this plate *y* is to 80 effect an air-tight closure for the trap door *w* when first starting the fire. Afterward the air-tight closure is effected by ashes raked over said trap door and the plate *y* may be dispensed with.

A convenient manner of arranging the trap door *w* is illustrated in Fig. 8. It is hinged at its rear end *z*, and the front end thereof is supported in horizontal position by a latch *2*, provided with a hole *2^a*, in 90 which is inserted a poker. When the latch is thrown up, as shown in dotted outline in Fig. 8, the trap door *w* will drop down, and when the trap door is lifted back to its horizontal position it will pass the nose of the 95 latch *2*, lifting the same out of the way, and the latter will then drop back to its normal position, and support the trap door.

By having reference to Figs. 1 and 5, it will be seen that the passage-way connecting the upper portion of the combustion chamber, *a*, with the controlling-draft chamber *g* is in the nature of a pipe. Instead of such construction, however, it may be found convenient where, for example, wood fuel 100 is to be used, to provide instead two ducts 3, 4, located at the sides, as shown in Figs. 6 and 7, thereby providing greater fuel space. The parts *l'*, *r'* of Fig. 7 are substantially the same as the parts *l*, *r* shown 105 in Fig. 5.

A fuel-opening, *n*, may be provided in the upper portion of the combustion chamber. Such fuel-opening is provided with a ground rim against which fits a door *o*, also made with a ground rim, so as to have an air-and-gas-tight fit when closed. The door *o* is provided with a central inwardly projecting stud screw *p*, which screws into a threaded aperture provided in the central portion 5 of the arm 6, provided with a bent portion 7 hinged to the inner side of the casing 8. The left end, 9, of the arm 6, as shown in Fig. 3, is adapted to constitute a latch engaging with a lug 10 provided on the interior of the casing 8. By lifting on the knob 11, the door *o* is slightly rotated, and simultaneously the latch-end 9 of the arm 7 is disengaged from the lug 10 and the door may be opened to throw in fuel. 130

In Fig. 4 is shown a convenient construction for the gate covering the air-inlet in the wall 12 of the draft-chamber *c*, this construction being disclosed in my Patent No. 1,058,025 dated April 1, 1913. The rim of the air-inlet *d* has a ground face against which abuts the rim of the gate *e*, also provided with a ground rim. To the casing 12 is hinged an arm 13, (see Fig. 4) the free end 14 of which is adapted to serve as a latch, engaging with a lug 15, provided on the interior of the casing 12. To regulate the inflow of air in excess of that admitted through perforations *f* of the gate *e*, the latter is set against and spaced from the casing 12 by a screw 16; in being so adjusted it is held against rotation by a pin 17, bearing in a perforation of the arm 13.

The hinge-feature, illustrated in Fig. 9, of the door *h* of the controlling-draft chamber *g* is important in this regard. When said door *h* is unlatched it is desirable that it stand merely ajar, and will not swing open wide, for when standing ajar it just admits sufficient excess of air through chamber *g* to put out the fire on the grate, while if the door *h* is opened too wide it is liable to cause my furnace to smoke. The door *h* is caused to stand ajar, as mentioned, by elongating the hole of the lug 23 for its upper hinge-pin 24, so as to make gravity hold the door in proper position.

In Fig. 6 the top of the combustion chamber is provided with an interior flange 19, providing an annular pocket in which to hold stove-putty, ashes, or other suitable substance. The top plate 20 is made with circumferential pendent flanges 21, seated air-tight in said pocket. The top-plate 20 is provided with a rim-flange 22, converting the same into a receptacle for holding water.

I claim:

1. In a heater, the combination of a combustion chamber sealed above the grate against the ingress of air, a grate in the bottom of the combustion chamber, a draft chamber below said grate and provided with an air-inlet adapted to admit continuously a minimum volume of air, means for controlling the air-inlet for regulating the admission of air to the draft chamber between the minimum and maximum supply, a draft controlling chamber separated from the draft chamber and having an outlet to the flue of the stack and an air-inlet opening opposite the outlet opening for creating a current of air through said chamber, a damper for controlling the admission of air through the air-inlet opening in the draft controlling chamber, and a diving flue extending from the combustion chamber above the bed of fuel and through the grate and communicating with said draft controlling chamber, said flue discharging into said air current in the draft controlling chamber.

2. In a heater, the combination of a combustion chamber sealed above the grate against the ingress of air, a grate in the bottom of the combustion chamber, a draft chamber below said grate and having an air-inlet adapted to admit continuously a minimum volume of air, a draft controlling chamber separated from the draft chamber and having an outlet to the flue of the stack and an air-inlet opening formed near the bottom and located opposite the outlet to create a current of air through the draft controlling chamber, a damper for controlling the air-inlet, and a flue extending from the top of the draft controlling chamber through the draft chamber and into the combustion chamber and terminating above the level of the fuel, said flue discharging into said air current in the draft controlling chamber.

3. In a heater, the combination of a combustion chamber sealed above the grate against the ingress of air, a grate in the bottom of the combustion chamber, a draft chamber below said grate and provided with an air-inlet adapted to admit continuously a minimum volume of air, a draft controlling chamber separated from the draft chamber and having an outlet to the flue of the stack and an opening near the bottom and opposite the outlet to create a current of air through the draft controlling chamber, a door for the opening, said door having an air-inlet, a damper for the air-inlet and a diving flue communicating with the combustion chamber above the bed of fuel and extending below the grate and into the top of the draft controlling chamber, said diving flue discharging into said air current in the draft controlling chamber.

4. In a heater, the combination of a combustion chamber sealed above the grate against the ingress of air, a grate in the bottom of the combustion chamber, means for introducing a regulated supply of air below the grate, a draft controlling chamber formed with opposite inlet and outlet openings, to create a current of air through the draft controlling chamber, the outlet opening being of lesser area than that of the inlet opening, means for regulating the admission of air in the inlet opening of the draft controlling chamber, and a diving flue extending from the combustion chamber above the bed of fuel and below the grate and terminating in the draft controlling chamber in a different plane than the plane of the air inlet and outlet openings therein, said diving flue discharging into the current of air in the draft controlling chamber.

5. In a heater, the combination of a combustion chamber which is sealed above the grate against the ingress of air, a grate in the bottom of the combustion chamber, means for introducing a regulated supply of

- air below the grate, a draft controlling chamber formed with an inlet opening and an outlet opening, said openings being opposite each other, and a diving flue communicating with the combustion chamber above the bed of fuel and extending below the grate and communicating with the upper portion of the draft controlling chamber above the level of the inlet and outlet openings therein, said diving flue discharging the products of combustion directly into the path of the air current flowing from the inlet to the outlet openings in the draft controlling chamber.
6. In a stove, the combination of a combustion chamber which is sealed above the grate against the ingress of air, a grate in the combustion chamber, a draft chamber, a draft controlling chamber located below the combustion chamber, an exit flue communicating with the draft controlling chamber, means for introducing to the draft chamber a constant minimum supply of air and a regulatable supply of air in addition to the constant minimum supply of air, both said supplies of air passing through the fuel to promote combustion in the combustion chamber, a flue communicating with the air tight combustion chamber above the plane of the top of the fuel and extending to and discharging into said draft controlling chamber, and an adjustable damper in the draft controlling chamber to regulate the current of air passing through said chamber to the exit flue, said air current acting on the products of combustion delivered from the exit of the flue to control the combustion in the combustion chamber.
7. In a heater, the combination of a combustion chamber sealed above the grate against the ingress of air, a grate in the bottom of the combustion chamber, a draft chamber below said grate and provided with an air-inlet adapted to admit continuously a minimum volume of air, a draft controlling chamber separated from the draft chamber and having an outlet to the flue of the stack and an air inlet opening to create a current of air through the draft controlling chamber, a door for the air inlet opening, said door having an air-inlet of smaller area than the stack, a damper for such air-inlet, and a diving flue communicating with the combustion chamber above the bed of fuel and extending below the grate and communicating with the top of the draft controlling chamber, said diving flue discharging into said air current in the draft controlling chamber.
8. In a stove, the combination of a combustion chamber the upper portion of which is sealed above the grate against the ingress of air, a grate in the bottom of the combustion chamber, a draft chamber below the grate and having an air inlet adapted to admit continuously a minimum volume of air, means for admitting a regulated maximum supply of air through the body of fuel in the combustion chamber, a draft controlling chamber, a draft flue extending from the combustion chamber above the bed of fuel and below the grate and discharging into said draft controlling chamber, means for creating a current of air through said draft controlling chamber so as to intersect the current of air discharging by the draft flue to the draft controlling chamber, and means for regulating the air current passing through the draft controlling chamber.
9. In a stove, the combination of a combustion chamber, a grate in the bottom of the combustion chamber, said combustion chamber being sealed above the grate against the ingress of air, an air tight fuel cover in the combustion chamber, a draft chamber below the grate, adjustable means for admitting a constant minimum supply of air and a regulatable supply of air in addition to the constant minimum supply of air to the draft chamber, a draft controlling chamber located in a lower plane than the combustion chamber, said draft controlling chamber having an air inlet opening and an exit opening, the combined area of the air inlets in the draft chamber and the draft controlling chamber being greater than the area of the exit opening, an adjustable damper for regulating the air admitted through the inlet opening in the draft controlling chamber, a flue communicating with the air tight combustion chamber above the level of the flue therein, said flue communicating with the draft controlling chamber and discharging the products of combustion above the level of the bottom of the exit opening, whereby the combustion in the combustion chamber may be controlled by a current of air passing through the draft controlling chamber, and the regulated supply of air passing through the fuel from the draft chamber.
10. In a heater the combination of a combustion chamber sealed against the ingress of air above the grate, a grate in the combustion chamber, a draft controlling chamber provided with an exit opening, a draft chamber communicating with the combustion chamber, a diving flue communicating with the combustion chamber above the level of the fuel therein and passing below said combustion chamber and discharging into the draft controlling chamber, means for admitting a minimum constant supply of air to the draft chamber to at all times promote a limited degree of combustion in the combustion chamber, and for introducing an increased volume of air to the draft chamber in excess to and separate from the minimum supply, and means for introducing a regulated supply of air to the draft controlling chamber.

6
chamber to retard the combustion in the combustion chamber, the said air being drawn through the draft controlling chamber under the influence of the draft in the exit flue and thereby overcoming the force of the draft from the diving flue and controlling the same at the discharge end of said diving flue.

11. In a stove, the combination of a combustion chamber sealed against the ingress of air above the grate, a grate in the combustion chamber, a draft controlling chamber provided with an exit opening, a draft chamber communicating with the combustion chamber and formed with openings for the admission of a minimum and constant supply of air to at all times promote a limited degree of combustion in the combustion chamber; a draft flue communicating 20 with the combustion chamber beyond the surface of the fuel therein and extending below the air tight combustion chamber and discharging into the draft controlling chamber, means for admitting a regulated supply 25 of air to the draft chamber in excess to and separate from the minimum supply, and means for introducing a regulated supply of air to the draft controlling chamber to retard the combustion in the combustion 30 chamber, the said air being drawn through the draft controlling chamber under the influence of the draft in the exit flue and thereby overcoming the force of the draft and controlling the same at the discharge end 35 of the draft flue.

12. In a stove, the combination of a combustion chamber, an air tight fuel cover in the combustion chamber, a grate in the bottom of the combustion chamber, said combustion chamber being sealed against the ingress of air above the grate, a draft chamber below the combustion chamber and provided with an opening to supply a constant current of air which passes through the 40 grate and the body of fuel, a draft controlling chamber located in a lower plane than the combustion chamber and provided with an inlet opening and an exit opening, a flue communicating with the combustion chamber above the level of the fuel therein and extending below the latter and discharging into the draft controlling chamber, and means for regulating the admission of air through the inlet opening in the draft 45 controlling chamber which with the constant current of air passing through the fuel under the influence of the draft in the exit opening, controls the discharge of the com-

bustion from the flue and regulates the combustion in the combustion chamber.

13. In a stove, the combination of a casing provided with a combustion chamber sealed against the ingress of air above the grate, an 60 air tight fuel cover for the combustion chamber, a grate in the bottom of the combustion chamber, a draft chamber below and communicating with the air tight combustion chamber through the grate, a draft controlling chamber below the draft chamber, a flue communicating with the air tight combustion chamber, above the bed of fuel and extending below the grate and communicating with the draft controlling chamber, said draft controlling chamber having an air inlet and an outlet, the draft chamber having an opening for admitting a constant supply of air to the bottom of the fuel, the 65 said opening being of less area than the area of the air inlet in the draft controlling chamber, and means for regulating the air inlet opening in the draft controlling chamber, whereby the maximum supply of air 70 will overcome the draft passing through the flue, and choke the combustion in the combustion chamber.

14. In a heater, the combination of a casing provided with a combustion chamber including a grate, an air tight fuel cover for 85 the combustion chamber, said combustion chamber being sealed against the ingress of air above the grate, a draft chamber under the grate, said draft chamber having air inlets for the admission of a constant minimum supply of air and a regulatable maximum supply of air in addition to the minimum supply of air to promote combustion in the combustion chamber, a draft controlling chamber, a diving flue communicating 90 with the draft controlling chamber and passing through the draft chamber and the grate and terminating in the combustion chamber above the level of the fuel, the draft controlling chamber having an exit flue communicating therewith, said draft controlling chamber having an air inlet opening, a damper for regulating the latter air inlet opening, and a damper controlled inlet opening 95 for admitting a current of air near the bottom of the draft controlling chamber whereby to control the discharge of the combustion from the diving flue and regulating the combustion in the combustion chamber.

100 MARY A. MALLOY.
